(57) **CLAIM**

The ornamental design for a reclosable locking lid assembly, as shown and described.

DESCRIPTION

FIG. 1 is a first anterior top perspective view of a reclosable locking lid assembly in a first condition of use.

FIG. 2 is a top plan view of the reclosable locking lid assembly in the first condition of use.

FIG. 3 is a posterior side elevational view of the reclosable locking lid assembly in the first condition of use.

FIG. 4 is an anterior side elevational view of the reclosable locking lid assembly in the first condition of use.

FIG. 5 is a first lateral side elevational view of the reclosable locking lid assembly in the first condition of use.

FIG. 6 is a second lateral side elevational view of the reclosable locking lid assembly in the first condition of use.

FIG. 7 is a bottom plan view of the reclosable locking lid assembly in the first condition of use.

FIG. 8 is a second anterior top perspective view of the reclosable locking lid assembly of FIG. 1 shown in a position of use attached to an unclaimed cup.

FIG. 9 is an anterior top perspective view of the reclosable locking lid assembly with the upper portion removed therefrom.

FIG. 10 is a top plan view of the reclosable locking lid assembly with the upper portion removed therefrom.

FIG. 11 is an anterior top perspective view of the upper portion of the reclosable locking lid assembly removed from the bottom portion.

FIG. 12 is a top plan view of the upper portion of the reclosable locking lid assembly removed from the bottom portion.

FIG. 13 is a first lateral edge view of the upper portion of the reclosable locking lid assembly removed from the bottom portion.

FIG. 14 is a second lateral edge view of the upper portion of the reclosable locking lid assembly removed from the bottom portion.

FIG. 15 is a posterior edge view of the upper portion of the reclosable locking lid assembly removed from the bottom portion.

FIG. 16 is an anterior edge view of the upper portion of the reclosable locking lid assembly removed from the bottom portion; and,

FIG. 17 is a bottom plan view of the upper portion of the reclosable locking lid assembly removed from the bottom portion.

The broken lines in FIG. 8 illustrating a cup depict environment and form no part of the claimed design. All other broken lines depict portions of the reclosable locking lid assembly that form no part of the claimed design.
